A. C. MENGES,
INLET VALVE FOR GAS ENGINES.
APPLICATION FILED FEB. 18, 1910.

1,113,810.

Patented Oct. 13, 1914.

UNITED STATES PATENT OFFICE.

ALBERT C. MENGES, OF MEMPHIS, TENNESSEE, ASSIGNOR OF ONE-HALF TO JOHN H. HINES, OF MEMPHIS, TENNESSEE.

INLET-VALVE FOR GAS-ENGINES.

1,113,810.

Specification of Letters Patent. Patented Oct. 13, 1914.

Application filed February 18, 1910. Serial No. 544,553.

To all whom it may concern:

Be it known that I, ALBERT C. MENGES, a citizen of the United States, residing at Memphis, in the county of Shelby and State of Tennessee, have invented certain new and useful Improvements in Inlet-Valves for Gas-Engines, of which the following is a specification.

My invention relates to inlet valves for gas engines and its object is to provide a device of the piston valve type provided with means whereby the ports for admitting the explosive mixture may be accurately formed and spaced at a less cost of manufacture than is usually required, and whereby the operation of the inlet valve is so timed as to permit of the full compressive action of the main piston upon the explosive mixture to be obtained, and generally to improve and simplify inlet valves of the above type.

To this end, my invention is embodied in preferable form in the device hereinafter described and illustrated in the accompanying drawings.

In the drawing the figure is a sectional view through the main cylinder and through the piston valve and also through a special form of speed regulating distributor intermediate the piston valve and the carburetor.

Referring to the drawing, a main piston 3 is mounted in the main cylinder 4 which is of the usual construction and said piston operates connecting rod 5 connected to the crank 6 of the main crank shaft 7.

Carried by the main crank shaft 7 is a gear wheel 8 which meshes with a gear wheel 9 engaging and adapted to drive a larger gear 10. The last named gear is fixed on an auxiliary crank shaft 11 to which is connected piston rod 12 pivoted at its outer end to a piston 13. The auxiliary crank shaft and its crank are mounted within a casing 14 which is secured to the cylinder 15 in which the piston 13 moves and which cylinder 15 is formed in the same integral casting in which the main cylinder is formed, thus providing a construction which is strong and simple. The casing 14 communicates with a chamber 16 formed by a suitable casing or shell and communicating with a suitable carburetor. The chamber 16 is adapted to contain a special regulating and gas distributing device the

specific construction of which need not be here described as it forms the subject matter of another application executed by me. The piston 13 is hollow and is adapted to receive a charge of the explosive mixture from the carburetor through the distributing chamber at each suction impulse of the main piston and said piston is provided with one or more transverse valve ports 17 through its wall, which ports are adapted to register in the reciprocal movement of the piston valve with the ports 18 formed in a circumferential lining member 19 within the cylinder 15. The cylinder 15 is cored out to form a longitudinal passage way 20 between the cylinder wall and lining and providing communication between the ports 18 and one or more outer ports 21 formed in the lining member 19. The lining member 19 provides an effective means of obtaining accurately cut ports at a minimum expense and avoiding the inaccuracy and the expense required by forming such ports by coring the shell of the cylinder wall itself.

The main piston and the piston valve are shown in the drawing at the moment when the main piston is descending on the down suction stroke and with this position of the main piston the inlet valve is so located that the ports 17 in the piston valve are in registry with the ports 18 in the lining; thus permitting the explosive mixture as it is drawn into the piston by the suction of the main piston to pass through the ports 18 and passage way 20 and thence through ports 21 from whence the charge is drawn through the passage way 22 leading from the piston valve cylinder to the main cylinder. The main piston continues to move inward or toward the main crank shaft while the piston valve at the same time continues to move outward or away from its crank shaft and the outward movement of the latter is continued during the return compression stroke of the main piston and by the time the main piston starts to compress the charge, the ports 18 and 21 will be covered by the piston valve and by the time the compression stroke is completed and at the proper time for the explosion of the compressed charge the piston valve will be at the outer end of its stroke with its outer face flush with the outer end of the cylinder. Any suitable form of ex-

haust valve may be employed in connection with the device. Similarly, the piston valve makes one inward movement, that is a movement toward its crank shaft, while the main piston is making both its firing and exhaust movements, thereby bringing the ports in the valve and in the lining in proper registry at the time when the main piston is just about to begin its intake movement.

10 By having the piston valve so timed in its operation that it will move outward or away from its crank shaft while the main piston is also moving outward away from the main crank shaft in its compressing stroke, and so that the valve will close the inlet ports before it reaches the end of its stroke, the area of the valve cylinder between the end thereof and the face of the valve will be added to the area of the main cylinder, and the opposing movements of the two pistons will give a greater amount of compression with an equal clearance space as compared with the ordinary puppet valve type of engine. At the same time warping 25 of the valves and consequent loss of compression is avoided and a noiseless valve mechanism and one without excessive wear is provided.

The piston valve 13 is formed with circumferential grooves in which packing rings 27 and 28, respectively, are mounted.

In this arrangement the operation is substantially the same as with the previously described device, the piston valve being shown advancing outward and with the ports uncovered to admit the charge on the intake stroke of the main piston. It continues said outward movement and closes the ports on the compression stroke of the 40 main piston.

Having thus described my invention, what I claim is:

1. In an explosive engine the combination with the main cylinder and its piston of an auxiliary inlet cylinder in direct communication with the main cylinder, a separate lining in said auxiliary cylinder having independent longitudinally spaced ports connected by a passageway formed in the structure behind said lining, a hollow piston valve in said auxiliary cylinder provided with a port intermediate of its length and adapted to register with the inner port of the lining, and means driven by the main piston for positively reciprocating said piston valve to control said lining ports, substantially as set forth.

2. In an explosive engine the combination with the main cylinder and its piston of an auxiliary inlet cylinder having an annular recessed portion near the upper end thereof

and an open outer end communicating with said main cylinder, a lining sleeve for said inlet cylinder adapted to bridge said annular recessed portion and having ports near each end of said annular recess and communicating therewith, a hollow piston closed at the top and having a port intermediate its ends adapted to slide within said lining sleeve and arranged with its head adapted to control the upper ports and the intermediate port therein adapted to control the lower port in said sleeve lining, substantially as set forth.

3. In an explosive engine the combination with the main cylinder and its piston of an auxiliary inlet cylinder having an annular recessed portion near the upper end thereof, a lining sleeve for said inlet cylinder adapted to bridge said annular recessed portion and formed with ports adapted to communicate with the upper and lower extremities thereof, a hollow piston closed at the top having a port spaced from said closed top a distance equal to the distance between said sleeve ports and an annular recess above its said port, a packing ring mounted in said recess in said piston, and means for reciprocating said piston, whereby when said piston is at the limit of its inward stroke a communication is established between the inward end of said inlet cylinder and its open upper end which communicates with the engine cylinder, substantially as set forth.

4. In an explosive engine the combination with the main cylinder and its piston of an auxiliary inlet cylinder having an annular recessed portion near the upper end thereof and an open end communicating with the main cylinder, a lining sleeve for said cylinder having vertically spaced ports adapted to communicate with each end of said recessed portion, a hollow piston closed at the top adapted to slide within said sleeve for controlling said ports, said piston having a port intermediate its ends adapted to register with the inner port in said sleeve, and the piston head being adapted to control said upper port, whereby a charge may be admitted from the lower part of said inlet cylinder through said piston port in register with said lower sleeve port into said annular recess and then through said upper sleeve port into the upper part of said inlet cylinder, substantially as set forth.

In testimony whereof I have affixed my signature in presence of two witnesses.

ALBERT C. MENGES.
